UNITED STATES PATENT OFFICE

GEORGE GALAN, OF PITTSBURGH, PENNSYLVANIA

PULVERIZING MILL

Application filed August 27, 1927. Serial No. 215,853.

This invention relates to certain novel improvements in pulverizing mills and is particularly though not necessarily adapted to such mills wherein coal is reduced to powdered form in order that it may be burned in 5 suitably constructed burners.

The salient object of my invention is to provide a pulverizing mill which will embody a feed arrangement such that the mill may be kept in continuous operation.

10 An object, ancillary to the foregoing, is to provide two or more feed mechanisms adapted to be arranged so that as one feed mechanism is rendered inoperative by jamming another feed mechanism will be thrown into operation.

15 Another object of the invention is to provide a pulverizing mill wherein a novel beater arrangement is provided for reducing the fuel to powdered form, this beater mechanism being so arranged that a complete pulverization of the fuel will take place.

20 A further object of the invention is to provide a pulverizing mill in which the operating parts will be so positioned that they may be expeditiously repaired individually without 25 altering the remaining parts.

25 A still further object of the invention is to provide a pulverizing mill which will be simple in construction and which will be economical to manufacture.

30 Other objects will appear hereinafter.

The invention consists in the novel combination and arrangement of parts to be hereinafter described and claimed.

The invention will be best understood by reference to the accompanying drawings, showing the preferred form of construction and in which:

35 Fig. 1 is a front elevational view of the device, certain parts having been broken away;

40 Fig. 2 is a longitudinal sectional view of my improved pulverizing mill;

45 Fig. 3 is a view partly in elevation and partly in section of the device looking in the opposite direction of Fig. 1;

50 Fig. 4 is a detail view of the beater or pulverizing mechanism; and

55 Fig. 5 is a detail view depicting an adjust-

able regulating member employed in the device.

Referring to the drawings, it may be seen that my improved mechanism is mounted on a base 10 and embodies a housing having end 55 walls 11 and 12. The brackets 13 and 14 are supported from the base 10 and are secured to the end walls 11 and 12 respectively. Bearings 15 and 16 are carried by the brackets 13 and 14 and are adapted to be aligned.

Suitable openings 17 and 18 are provided in the end walls 11 and 12 respectively and a drive shaft 19 extends through these openings and is journaled in the bearings 15 and 16. Power is adapted to be supplied to the 60 shaft 19 at the end 20 thereof, a suitable connection being provided at this point. The mill may be either driven by a direct connection to the power supplying mechanism or it may be connected thereto through a gear train 65

or other analogous means.

On the drive shaft 19 at the opposite end from the end 20 thereof, a worm gear 21 is provided. Adapted to mesh with the worm gear 21 is a worm wheel 22 that is suitably keyed to the shaft 23. The brackets 24 and 25 are carried by the bracket 13 and have 70

bearings such as 26 therein in which the shaft 23 is adapted to be journaled. A suitable housing 27 is provided around the just described mechanism and has a removable cover 75

28 so as to afford access to the interior of the housing 27.

An opening 29 is provided in the end wall 11 and a housing 30 is disposed so as to be in communication with the beater mechanisms through the opening 29. The housing 30 is secured to the end wall 11 and defines a chamber 32 in which the feed mechanisms are 80

adapted to be mounted. Disposed on the upper side of the chamber 32 is a hopper 33 and controlling communication between said hopper 33 and said chamber 32 is a slide door 34. Suitable bearings are provided in the 85

walls of the housing 30 and journaled in these 90 bearings is a shaft 35 on which a feed roller 36 is adapted to be keyed. The feed roller 36 embodies a plurality of openings such as 37 which are waved or contorted in form as is best shown in Fig. 1. The coal or similar 95

100

fuel is adapted to be supplied to the device from the hopper 33 through the openings 37, in the feed roller 36, that are adapted to be of a predetermined size intended to limit the size of fuel which may pass thereby. The particular location of the feed roller with respect to the hopper 33 and discharge opening 29 is best shown in Fig. 2. An adjustable baffle plate 38 is located so as to direct the fuel from the hopper 33 into the openings 37 in the feed roller 36. A baffle member 39 is disposed on the opposite side of the feed roller 36 from the baffle plate 38 so as to insure proper direction of the incoming fuel and to limit the size of the fuel which may pass thereby. Another baffle plate 40 is mounted in the chamber 32 and defines an opening 41 in a wall of the housing 30, said opening being disposed between the baffle plates 38 and 40. The waved openings 37 in the feeder 36 are adapted to be disposed in a manner such that the various portions thereof will be similarly disposed. The baffle member 39 is disposed so as to prevent travel of the coal by the feed member 36 and to insure direction thereof into the openings 37. Thus it may be seen that the feeder member 36 is disposed so as to permit only a regulated amount of coal to be discharged into the portion of the chamber 32 juxtaposed to the opening 29.

By referring to Fig. 1, it may be seen that two feeder members such as the one just described are provided. These feeder members are located on opposite sides of the drive shaft 19. The additional member comprises a feed roller 36' that is mounted on the shaft 35', these parts being similar to the shaft 35 and the feeder 36.

Mounted on the shaft 35' is a sprocket 42 and mounted on the shaft 23 in alignment with the sprocket 42 is a sprocket 43 and a suitable chain belt 44 interconnects these two sprockets. It is to be understood that any other analogous power of transmitting mechanism might be substituted in place of the just described chain belt drive and still not depart from the purview of my invention.

The side walls of the housing 45 of the pulverizing mill are arranged so as to embody a portion defining the shoulder 46. This shoulder 46 in co-operation with the end wall 11 defines a chamber 47 that will be known hereinafter as the beater chamber. Mounted in the chamber 47 on the shaft 19 are the beater members 48 which pulverize the coal in a well-known manner. Fig. 4 is a detail view of the beater members. The coal is passed through the opening 29 and collects in the bottom of the chamber 47 where it is acted on by the beaters 48 which pick up the coal and act to crush it. This crushing action is enhanced by the abrasion of the particles of coal one on another. The speed of operation, and the arrangement of the beaters, de-

termine the completeness of the pulverization and the magnitude of the particles.

The end walls 45 of the pulverizing mill housing define a shoulder 60 which is spaced away from the end wall 12 so as to define therebetween a chamber 61 in which a fan 62 is mounted on the shaft 19. The walls 45 of the housing define a reduced passage 63 between the shoulders 46 and 60 and mounted adjacent the shoulder 46 so as to control passage into the chamber 63 is an air controlling device 64 which is arranged so that the openings therein may be adjustably varied. The device 64 is comprised of two divisible sections which are clamped on the shaft 19 so as to be rotatable therewith. As the fan 62 rotates, the air is drawn through the beater chamber and pulverized coal picked up and drawn past the controlling device 64, the amount of air and fuel passing this member being controlled by the size of the openings therein. The fan 62 may be arranged so as to embody any desired number of blades.

By referring to Fig. 1, it may be seen that an air supplying conduit 64', which embodies branches 65 and 66 that are directed into the chambers 32 and 32' of the feeder mechanism through suitable openings provided in the walls of these chambers, is provided. The branch 65 communicates with the chamber 32 through the opening 67 (Fig. 2). If desired, the conduit 64' may be directed to a point at which the air may be heated before its admission into said conduit and while this is preferable, it is not necessary for proper operation of my device. The rotation of the fan 62 will cause the air to be drawn from the conduit 64' through the opening 29 to the beater chamber 47 past the control device 64 into the chamber 63 and thence into the chamber 61 which is in communication with the discharge opening 68. An auxiliary air opening 69 is provided in the passage 63 so that additional air may be mixed with the air and fuel passing through this passage. In the wall 12 of the housing an air register 70 is mounted which has an opening 71 therein and communication through these openings 71 is controlled by the shutters 72. The shutters 72 are arranged so as to be adjusted in order that the quantity of air adapted to pass through the register 70 may be regulated. The speed of operation of the fan 62 determines the speed of air passage through the chamber 47, and this in turn regulates the size of the particles of pulverized coal that will be picked up and carried by the air.

The sprocket 43 is mounted on the clutch member 74 that is rotatably mounted on the shaft 23. Preferably the sprocket 43 is keyed to the clutch member 74 in order that said clutch member may be moved without altering the position of the sprocket 43. As stated, rotation of the sprocket 43 is conveyed to the sprocket 42 through the chain belt 44.

or other analogous means. The clutch member 73 is securely keyed on the shaft 23. A jaw formation comprised of the tongue member 92 and the recess 93 is provided and this construction is such that when the clutch is engaged so as to operate the feed roller 36' in the manner described, jamming of the feed roller 36 will cause the clutch to operate and due to the wedge formation of the part 92 5 the clutch member 73 and 74 will be cammed apart. A spring 76 is disposed around the shaft 23 between the slideable clutch member 74 and the member 75 which is securely fixed to the shaft 23. This spring serves to 10 hold the clutch in engagement. When the clutch is cammed apart in the manner described the retaining member 77 slides along the outer surface of the clutch member 74 and comes into the position depicted in Fig. 1 15 wherein it holds the clutch in disengaged position. The clutch retaining member 77 is pivotally mounted at 90 and includes a portion 91 to which the rod 78' is attached. The opposite end of the rod 78' is attached to the 20 clutch actuating member 80' which is disposed on the opposite side of the device and which is adapted to operate the mechanisms which will drive the feed roller 38, these mechanisms being identical with those disposed 25 in connection with the feed roller 36. As the clutch retaining member 77 comes into the position described, it acts on the member 80' to cause engagement with the clutch which will drive the feed roller 36. 30 Thus the feed roller 36 will be brought into operation as the feed roller 36' jams and if desired a suitable warning signal may be provided on these feed mechanisms in order that the operator of the device may be apprised 35 of the fact that one of the feed mechanisms has jammed in order that he may determine the cause thereof and remove it so that this feed mechanism will be ready to function in the event the other feed mechanism jams. 40 When the clutch actuated by the clutch operating member 80' engages the clutch retaining member 77' will be cammed down so as to rest on the outer surface of the slideable 45 clutch member 74'. Certain of these parts are not shown in the drawings but since they are identical with the parts shown they are indicated by primed numbers. However, when the feed roller 36 jams the clutch retaining member will move into the position similar to that occupied by the clutch retaining member 77 in the same manner as that described for the clutch retaining member 77. Since the clutch retaining member 77' 50 is pivotally mounted at 90' and inasmuch as the rod 78 is pivotally connected to the portion 91' of the clutch retaining member 77' and since the opposite end of the rod 78 is connected to the clutch operating member 75 55 the clutch which operates the feed roller 36' will be caused to engage. It is apparent that when either of the clutches are thrown out of operation the members 80 and 80' are thrown into the position indicated in Fig. 1 and these members have notches 82 and 82' 60 formed therein which are engaged by the tips of the leaf springs 81 and 81' which serves to hold these clutch operating members in the position indicated in Fig. 1 which is the operative position. It is this movement of the clutch operating members 80 and 80' which causes the operation of the clutch retaining members 77 and 77' in the manner described. It is apparent that if desired these clutches may be manually manipulated 65 through the rods 78 and 78' so that both may be thrown out of service or both may be thrown into service at the same time. 70 The foregoing mechanism provides a pulverizing mill which may be kept in continuous operation and one in which the thorough pulverization of the coal is obtained. The construction is such that only pulverized fuel will be admitted from the device due to the 75 novel manner in which the pulverized fuel is picked up. 80 While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and 85 modifications as come within the scope of the 90 appended claims. 95 Having thus described my invention, what I claim as new and desire to protect by Letters Patent is: 100

1. In a delivery device, a pair of rotatable elements having openings of a predetermined size formed in the periphery thereof and adapted to extend axially thereof, means for independently directing fuel to said rotatable elements, a drive shaft, clutch members associated with said drive shaft, operating means for said clutch members, means for connecting said clutch operating means whereby when one of said clutches is disengaged the other of said clutches will be engaged whereby to independently connect said rotatable elements to said drive shaft for rotation therewith. 105

2. In a delivery device, a pair of housings, 110 hoppers associated with the inlet openings of said housings, rotatable members mounted in said housings below said hoppers, said rotatable members having openings of a predetermined size formed in the periphery thereof and adapted to extend longitudinally thereof, guide plates carried by said housing adapted to be disposed to direct material introduced through said hoppers to the openings in said rotatable members, a drive shaft, 115 means for including clutches adapted to se- 120

125

130

lectively connect said rotatable members to said drive shaft, operating means for said clutches, means for inter-connecting said operating means, said last named means being 5 adapted to engage one of said clutches as the other of said clutches is disengaged whereby to independently rotate said rotatable members.

3. In a delivery device, a pair of housings, 10 hoppers associated with the inlet openings of said housings, rotatable members mounted in said housings below said hoppers, said rotatable members having openings of a predetermined size formed in the periphery 15 thereof and extending longitudinally thereof, guide plates carried by said housings disposed to direct material introduced through said hoppers to the openings in said rotatable members, a drive shaft, an operating shaft 20 driven by said drive shaft, clutch members on said operating shaft, clutch members associated with said first named clutch members, means for connecting said second named clutch members and said rotatable elements, 25 means for operating said clutches, and means for interconnecting said clutch operating means whereby when one of said second named clutches is disengaged from one of said first named clutches the other of said 30 second named clutches will be engaged with the other of said first named clutches.

In testimony whereof I affix my signature.
GEORGE GALAN.
